UNITED STATES PATENT OFFICE.

SEDGWICK N. WIGHT, OF ROCHESTER, NEW YORK, ASSIGNOR TO GENERAL RAILWAY SIGNAL COMPANY, OF GATES, NEW YORK, A CORPORATION OF NEW YORK.

AUTOMATIC TRAIN-CONTROL SYSTEM.

Application filed March 18, 1921. Serial No. 453,302.

To all whom it may concern:

Be it known that I, SEDGWICK N. WIGHT, a citizen of the United States, residing at Rochester, in the county of Monroe and State of New York, have invented certain new and useful Improvements in Automatic Train-Control Systems, of which the following is a specification.

This invention relates to automatic train control systems for single track railroads, and more particularly to the track equipment and the controlling circuits of such a system.

On single track railroads protection must be provided for train movement in either direction, that is, protection for trains traveling in opposite directions toward each other (opposing movements), and trains traveling in the same direction as on double track railroads (following movements). These and other requirements for single track operation of trains have been satisfied, so far as signal indication is concerned, by the type of automatic block signal system now commonly known as an absolute-permissive-block system.

There are various types of train control systems employing different forms of car apparatus and track devices, but in those types which operate in accordance with the principle of failure on the side of safety, the trackway means is such that it is placed in the proceed or safety condition by the closing of a circuit or the like, and is automatically changed to its danger or stopping condition when such circuit is broken.

The present invention is primarily directed toward providing an arrangement of circuits and devices for use in connection with an A. P. B. system which will open and close the controlling circuits for the track devices of the train control system, in such a way that said track devices will communicate the desired impulses or influences to passing trains in proper conformity with the signal indication. Other specific objects and advantages of the invention will appear hereinafter.

In the accompanying drawing, Fig. 1 is a diagrammatic view showing one arrangement of the signals in an absolute-permissive-block system;

Figs. 2 and 3 are simplified diagrammatic views of two arrangements of controlling circuits for the track element at a signal lo-

cation, where there are oppositely located opposing signals;

Fig. 4 is a diagrammatic view of one typical form of car equipment, and illustrates the way in which it cooperates with the track element; and

Figs. 5, 6, and 7 are simplified diagrammatic views showing other arrangements of controlling circuits for the track element, which are more particularly applicable to a signal location where there is only one signal.

The controlling circuits embodying the invention have been shown in the form which they will take in connection with the particular A. P. B. system disclosed in my prior Patent No. 1,294,736, dated Feb. 18, 1919, but by simple modifications and adaptations readily apparent to those skilled in the art, the same principles may be applied to A. P. B. systems of other specific forms. Since the detail construction and operation of the A. P. B. system of my prior patent is fully shown and disclosed in said patent, it will be sufficient, in order to obtain a clear understanding of the present invention, to explain this A. P. B. system merely in a general way, and without attempting to point out the detail construction, circuits and mode of operation.

Fig. 1 illustrates one arrangement of signals for an A. P. B. system. The stretch of single track (shown by a single heavy line) between two passing sidings X, is divided into track sections A—B—C etc., in the usual way by insulated joints 2. Signals, designated S¹ to S⁸, are located at intervals along this stretch of single track, and in the arrangement shown, these signals are arranged in pairs. The two signals S² and S⁷ at each end of the stretch and controlling train movement into the stretch, are known as the absolute or starting signals, and are made distinguishable in some suitable way, as by the shape of the blade and marker lights, from the other signals, these starting signals, when in the stop position, signifying "stop and stay." The other signals are permissive signals, and when in the stop position, signify that the train may proceed in accordance with certain prescribed rules, expecting to find another train or other obstruction ahead.

The general scheme of operation of the A. P. B. system schematically illustrated in

Fig. 1 is as follows: When a train enters the stretch of single track from either end, it causes all of the opposing signals to assume the stop position, thereby blocking 5 trains approaching in the opposite direction. As this train travels through the stretch of single track, these opposing signals are held in the stop position until passed by the train. The signals behind this train are caused to 10 assume in turn, the stop, the caution, and the clear positions, so as to permit following movements under signal protection the same as in double track block signal systems. The circuits and devices employed in 15 obtaining this operation of the signals are fully explained in my prior patent; and for the purpose of describing the present invention, it is sufficient to note that the track between successive signals, as S^2-S^4 , is divided into two track sections, as A—B, each provided with a track battery (not shown) 20 and a track relay 3, the track relays being located at the ends of the track sections nearest the signals, and that there is a polarized line relay L at each signal for controlling the position thereof.

In the present invention it is assumed that the track elements of the train control system are of the type which is caused to 30 assume the inactive or proceed condition when a controlling circuit therefor is closed, and the active stopping condition when said circuit is opened, this circuit including a source of energy, or being merely a conducting 35 path, according to the particular type of train control system. While various forms of track elements may be employed in connection with this invention, I have selected 40 for illustration a track element which acts inductively through an intervening air gap to influence suitable car apparatus. This track element produces its stopping effect by virtue of its magnetic qualities, and may be said to be of the inert type. Referring to 45 Fig. 4, this track element T shown comprises a U-shaped iron core 4, with enlarged pole pieces 5, and is provided with a coil 6 on each leg, said coils being wound and connected in series so as to be cumulative in 50 their effect when flux passes through said core.

The car element for cooperating with this particular form of track element, comprises a similar U-shaped iron core or yoke Y, with enlarged pole pieces 7, and is supported on the locomotive or other vehicle in any suitable manner so as to pass directly over the track element T. On one leg of the yoke Y is a coil or winding 8, conveniently termed the primary coil; and on the other leg is another coil 9, conveniently termed the secondary coil. The primary coil 8 is energized by a battery 10, and to check the integrity of this energizing circuit, a balanced 55 relay R¹ is included in said circuit. This

relay R¹ is provided with an armature 11 biased by an adjustable spring 12, which is adjusted so as to balance the attraction exerted on the armature when the normal current flows. The armature 11 carries a head 70 of insulating material which is disposed between movable contact springs or fingers 13—14 cooperating with stationary contacts (indicated conveniently by arrows). If the battery 10 should depreciate, or the energizing 75 circuit for the primary coil 8 break, the spring 12 overcomes the attraction of the relay R¹ and moves contact spring 14 away from its cooperating fixed contact, thereby breaking the circuit which includes in series 80 the springs 13—14 and their fixed contacts. Likewise, if the primary coil 8 should be short-circuited, the current in the relay R¹ increases above the normal and attracts the armature 11 in opposition to the spring 12, 85 so as to move contact spring 13 out of engagement with its cooperating fixed contact, thereby breaking the circuit.

The secondary coil 9 is connected to a relay R which is constructed the same as the relay R¹, with such changes in the windings or the like that may be desirable to obtain the required operating characteristics. The relay R and the secondary coil are connected in series with a battery 15, which preferably 90 has a low voltage. If this circuit becomes broken, or the secondary coil 9 short-circuited, the relay R opens its contacts in the same way as above described. Also, if the normal current through said relay is increased or decreased by induced voltage in the secondary coil 9, the relay R opens its contacts. 95

Any suitable form of train control apparatus may be governed by the relays R and R¹; but since the type of this apparatus has no bearing upon the present invention, there is illustrated a device K, in the form of an electro-pneumatic-valve, which upon being deenergized may be used to vent the train 105 pipe and apply the brakes at once, or set into operation speed control equipment or any other suitable train control mechanism. The device K is included in a normally 110 closed circuit energized by a battery 16 and interrupted when the contacts of either of the relays R or R¹ are opened. 115

When the coils 6 of the track element T are open-circuited, the core 4 of this element presents in effect a dead magnetic loop for the yoke Y of the car element, and when said car element passes over this magnetic loop, the reluctance of the partial magnetic circuit through said yoke is changed, thereby producing a change in the flux through the secondary coil 9. This change in flux induces in the secondary coil 9 an electro-motive-force, alternating in character, which alternately opposes and assists the 120 voltage of the battery 15, thereby varying 125

the current in the relay R and causing it to open its contacts and deenergize the device K. If the coils 6 of the track element are in a closed circuit of low resistance, they 5 serve to oppose or choke back the passage of flux through the core 4, so that as the car element passes over said core, there is no appreciable change in the flux through the secondary coil 9, and the relay R is not 10 operated.

Thus, if the coils 6 of the track element T are open-circuited, an impulse is transmitted to the passing vehicle which may be utilized in any desired way to control its 15 movement; but if said coils are in a closed circuit, the vehicle may pass without receiving such an impulse. In other words, with the circuit through the coil 6 closed, the track element is in its safety or proceed position, and with this circuit open, said element is in the active stopping or 20 danger condition.

The particular car and trackway equipment shown in Fig. 4 and above described 25 forms no part of the present invention and is disclosed and claimed in other applications.

According to the present invention, the track elements T are located on the center 30 line of the track so that they will co-operate with the car equipment on a vehicle traveling in either direction. It is necessary, therefore, to provide controlling circuits for the track element such that it will give the 35 desired opposing and following protection, but will not transmit a stopping impulse at the wrong time; and the subject matter of the present invention consists primarily in an arrangement of controlling circuits for 40 accomplishing this result.

Fig. 2 shows one arrangement of controlling circuits embodying the invention and particularly applicable for signal locations where there are two opposing signals 45 located opposite each other. Since the same arrangement is employed for each signal location, a description of one will suffice for all. The signals S³ and S⁴ are controlled by polarized line relays L³ and L⁴, respectively, in the usual way, and since these control circuits are well-known and are clearly shown, no detail explanation will be given. It is noted here that these circuits have been shown according to the convention 50 in which the letter B indicates a connection to one terminal of a battery or other source of current, and the letter C a connection to the other terminal of said battery, either directly or through a common wire for the 55 system.

The track element T is preferably located directly opposite the insulated joints 2 between the track sections B and C. The coils 6 of said track element are provided 60 with two circuits in multiple. When either

of these circuits is closed, the track element T is in its safety proceed condition, and with both of said circuits open, the track element is in its stopping condition. These circuits include neutral and polar contacts 70 on the line relays of the respective signals, so that each of said circuits are open when the corresponding signal is in the caution or stop position. For example, if the signal S⁴ is in the clear position, the coils 6 of the track element are in a closed circuit which may be traced as follows: Commencing at one coil 6, wire 20, polar armature 21 of the line relay L⁴, wire 22, neutral armature 23 of said line relay, and wire 24 to the other coil 6. This circuit will be opened at the polar armature 21 when the signal S⁴ is in the caution position, and at the neutral armature 22 when the line relay is deenergized to give a stop indication. In other words, if either one of the signals S³ or S⁴, 85 is in the proceed position, the track element is in the safety condition, but if both of said signals are in either the caution or stop position, said track element is in the active 90 stopping condition.

The arrangement shown in Fig. 2 operates in the following manner. Suppose a train is traveling from left to right, in the direction of traffic governed by the signal S⁴. 95 As the train approaches track element T, the opposing signal S³ is in the stop position to block opposing train movements by virtue of the control of signal S³ fully explained in my prior patent. 100

The condition of the track element T, therefore, depends upon the line relay L⁴, which in turn is controlled by trains ahead of the train in question and traveling in the same direction. If there is no other train 105 ahead, and the signal S⁴ is in the clear position, the coils 6 of the track element T are in a closed circuit, and train may pass without receiving a stopping impulse. If, however, there should be another train ahead, 110 either in the next or succeeding block, and the signal S⁴ is in either the stop or caution position, the coils 6 are open-circuited, and a stopping impulse will be communicated to the passing train. The same mode of operation is true for train movements in the opposite direction from right to left, the control of the track element being then governed in accordance with the indication of signal S³, the signal S⁴ being in the stop 115 position. In this way, the arrangement of controlling circuits shown in Fig. 2 provides for governing trains traveling in either direction in accordance with the signal indication. It should be understood that 120 the car element is carried on the locomotive or the leading vehicle of the train so that it passes over the track element before the line relay of the next track section in advance has been deenergized by the front end 125 130

of the train itself. In most cases it is found preferable to support the car element directly back of the pilot in front of the pony-truck.

5 The same control shown in Fig. 2 may be applied to each of the pairs of signals shown in Fig. 1; and except in one case, the stopping impulse is transmitted only when it is necessary for the train to stop. To illustrate the exceptional case, suppose there is a train on the main track opposite one of the sidings X, then an approaching train about to enter the siding will receive a stopping impulse upon passing the signal S⁸, since both the signals S⁷ and S⁸ are in the stop position. It may or may not be objectionable to receive a stopping impulse under these said circumstances, depending upon the type of train control apparatus. If the 20 system is one enforcing speed restrictions, or one in which a permissive control is imposed, a stopping impulse in this particular instance does no harm, and strictly speaking, is proper. If desired, the controlling condition of the track element at the starting signals may be made dependent upon the position of the switch leading to the siding, or upon some manual action on the part of the trainman throwing the switch.

30 Fig. 3 shows an arrangement operated in the same way as that shown in Fig. 2, the only difference being that the controlling circuits for the track element are taken through circuit controllers O³ and O⁴ operated by the signals S³ and S⁴, instead of through neutral and polar contacts of the line relays. These circuit controllers O³ and O⁴ are shown in accordance with established convention, and are closed only when the corresponding signal is in the clear position.

35 Instead of arranging the intermediate signals in pairs opposite to each other, as shown in Fig. 1, a staggered arrangement of intermediate signals is sometimes employed, that is, signals S³ and S⁶ are omitted, and the intermediate signals S⁴ and S⁵ used alone to give the desired opposing and following protection. In such an arrangement, there will be only one signal at each intermediate signal location, so that the circuit arrangement of Figs. 2 and 3 is not applicable.

40 Fig. 5 illustrates a modified construction for use with such staggered intermediate signals. In this arrangement, the track element T is provided with two multiple controlling circuits as before, and one of these circuits is taken through the neutral and polar contacts of the line relay L⁴, or through a circuit controller operated by the signal S⁴. The other circuit includes a front contact of the track relay 3^B of the track section B next in the rear of the signal in question. When a train travels from left to right, in the direction of traffic governed by signal S⁴, it shunts the track relay 3^B

and opens one of controlling circuits for the track element T before it reaches said element, so that the controlling condition of said track element is dependent upon the indication of signal S⁴ as before. A train 70 traveling in the opposite direction, however, will pass the track element before shunting the track relay 3^B, and consequently will pass said track element without receiving a stopping impulse, in spite of the fact that 75 the signal S⁴ will be in the stop position.

Fig. 6 shows a similar arrangement for a single signal location, more particularly designed to give a stopping impulse if this signal is in the caution position though not necessarily if the signal is in the stop position. In this arrangement, one of the two controlling circuits for the track element T is taken through a back contact of the track relay 3^C of the track section next in advance 80 of the signal S⁴. A train traveling in the direction of traffic governed by the signal S⁴ will pass the track element before dropping the track relay 3^C, and consequently 85 the controlling condition of said track element is dependent upon the indication of said signal. A train traveling in the opposite direction, however, will drop track relay 3^C and put the track element in the safety condition, before the track element 90 is passed.

95 Fig. 7 shows a modification of the arrangement illustrated in Fig. 6, and provides for a stopping impulse at a stop signal, as well as a caution signal, which does not necessarily follow in the arrangement 100 shown in Fig. 6. To illustrate, with the arrangement shown in Fig. 6, suppose there is a train on the track section C, then a following train will not receive a stopping impulse, because the track relay 3^C is down. In the modified arrangement shown in Fig. 7, the controlling circuit for the track element, which includes the back contact of the track relay 3^C, also includes a back contact 105 31 of the stick relay 30 associated with the signal S⁴, this stick relay being one of the characteristic parts of the A. P. B. system. The control of this stick relay is fully explained in my prior patent, and need be 110 reviewed only briefly. The pick-up circuit for said stick relay may be traced as follows: Commencing at one terminal of the battery (indicated by B) through contacts of circuit controller 32 operated by signal 115 S⁴ and closed between about 35 to 90°, wire 33, back contact 34 of track relay 3^C, wires 35—36, stick relay 30 to the other terminal of the battery (indicated by C). A train traveling from left to right picks up the stick relay, because it closes this pick-up circuit at back contact 34, the circuit controller 32 remaining closed for a short interval.

120 Trains traveling in the opposite direction do not pick up the stick relay be- 125 cause the track relay 3^C is down. The stick relay 30 is connected to the track element T, so that when the stick relay 30 is up, the track element T is 130 controlled by the signal S⁴ as in Fig. 6.

cause they open its pick-up circuit at the circuit controller 32 before they drop track relay 3^c and close its back contact 34. The stick relay 30, when once picked up, is maintained energized by a stick circuit as follows: Commencing at B, back contact 37 of line relay L⁴, wire 38, front contact 39 of the stick relay itself, wires 40-36, and stick relay 30, to C. Assume there is a train on the track section C, the back contact of track relay 3^c will be closed, but if this train entered said track section from the track section B, stick relay 30 was picked up, so that the track element behind said train in the track section C will transmit a stopping impulse to a following train. A train approaching in the opposite direction, that is, from right to left, is able to pass the track element T without receiving a stopping impulse in the same way as described in connection with Fig. 6, the stick relay 30 in this case remaining deenergized.

From the foregoing it will be observed that this invention provides an arrangement of controlling circuits for track elements by means of which the controlling condition of said elements may be automatically set up to conform with the signal indication, even though the trains move in either direction past said track element. Generally stated, this is accomplished by providing two controlling circuits for the track element, each of which may be said to correspond to one direction of train movement. If there is a pair of opposing signals at the signal location, these two circuits for the track element are governed in accordance with the signal indications. If there is only one signal at a signal location, one of these circuits is controlled in accordance with the indication of that signal, and the other by the track circuits in such a way as to prevent an opposing train traveling opposite to the direction of traffic governed by said signal from stopping itself.

The particular constructions and arrangements of circuits and devices herein shown and described are obviously susceptible of various modifications and adaptations to suit various types of train control systems and different forms of single track automatic block systems, and I desire to have it understood, therefore, that the embodiments of the invention shown and described are merely illustrative of its nature and mode of operation.

What I claim is:—

1. In a train control system for single track railroads provided with track circuits, the combination with a track element having an inherent tendency to assume an active stopping condition and adapted when in that condition to communicate a stopping influence inductively through an intervening air gap to a train traveling in

either direction thereby, said track element including an iron core and a winding thereon, two separate control circuits for said track element each passing through said winding, said track element being in the same inactive condition if either of said circuits is closed, and means controlled by a plurality of track circuits on opposite sides of the track element for separately and independently governing said circuits. 75

2. In a train control system for single track railroads provided with track circuits, and having oppositely located intermediate signals between sidings, said signals governing traffic in opposite directions, the combination with a track element associated with said signals and having two control circuits each adapted when closed to cause said element to assume the same inactive proceed condition, of means subjected to the same controlling influence as said signals for controlling said circuits separately. 80

3. In a train control system for single track railroads provided with track circuits, and having oppositely located intermediate signals between sidings, said signals governing traffic in opposite directions, the combination with a track element associated with said signals and having two control circuits each adapted when closed to cause said element to assume the same inactive proceed condition, of circuit controlling means in each of said circuits closed when the track circuits governing the corresponding signal are not occupied. 90

4. In a train control system for single track railroads equipped with an absolute-permissive-block system having opposite intermediate signals, a track element opposite each pair of intermediate signals, and means for placing each track element in the inactive condition unless both signals associated therewith are in the caution or stop position. 105

5. In an automatic train control system for single track railroads equipped with an A. P. B. system having pairs of opposite intermediate signals, a track element opposite each pair of signals, and means whereby the controlling condition of said track elements is automatically caused to correspond with the indication of the associated signal governing traffic in the direction in which a train approaches that track element. 110

6. In a system of automatic train control for single track railroads, a track element comprising a non-magnetized iron core disposed symmetrically with respect to the center line of the track so as to influence co-operating receiving elements on the vehicle traveling by said element in either direction, a winding on said core, a normally closed de-energized circuit of low resistance including said winding and adapted when closed to place said track element in its inactive con- 120

- dition, and automatic means for opening said circuit upon the approach of a train to said track element from either direction if there is another train in advance.
7. A train control system for single track railroads comprising, a track element effective when in the stopping condition to transmit impulses inductively to trains traveling in either direction, said track element having a control winding, two control circuits for said element each passing through said winding and each acting if closed to render said element ineffective to transmit an impulse to a passing vehicle traveling in either direction thereby, and automatic means for maintaining closed one or the other of said circuits during the movement of the train in one direction or the other past said element provided there is no other track element in the direction of which said passing train is traveling.
8. In an automatic train control system for single track railroads provided with track circuits, a signal governing traffic in one direction, a track element opposite said signal and having a normally closed control circuit adapted so long as closed to cause said element to assume its inactive condition, and means controlled by a track circuit in the rear of the signal for opening said control circuit.
9. In a train control system for single track railroads provided with track circuits, the combination with a signal, of a track element located opposite said signal and comprising an iron core and a coil thereon, said track element having two control circuits each including said coil and adapted when closed to cause said element to assume its inactive condition, means for controlling one of said circuits to conform with the indication of the signal, and means controlled by a track circuit in the rear of the signal for governing the other control circuit.
10. In a system of train control for single track railroads having track circuits, a signal governing traffic in one direction, a track element located opposite the signal and having a normally closed control circuit which normally maintains said element in its inactive condition, and means for opening said control circuit before a train traveling in the direction of traffic governed by said signal reaches said element and for maintaining said circuit closed until after the first vehicle of a train traveling opposite to the direction of the traffic governed by said signal has passed said track element.
11. In a train control system for single track railroads equipped with a block signal system of the type described, the combination with a pair of oppositely located intermediate signals of said block signal system, a track element adjacent to the signals and comprising a core and a coil thereon, a circuit controller operated by each signal of the pair and closed only if that signal is in the proceed position, and separate circuits governed by the respective circuit controllers and each including the coil of said track element.
12. In a train control system for single track railroads equipped with a block signal system of the type described, the combination with a signal, a track element disposed substantially opposite the signal and comprising a non-magnetized core and a coil thereon, a circuit including the coil and closed if the signal is in the proceed position, and another separate circuit including the coil and governed by a track circuit in the rear of the signal.
13. In a train control system for single track railroads equipped with a block signal system of the type described, the combination with a signal, a track element disposed symmetrically with respect to the center line of the track and adjacent to the signal so as to influence cooperating car apparatus on a vehicle traveling in either direction thereby, said track element comprising an iron core and a coil thereon, two circuits each passing through said coil, and automatic means comprising said circuits for maintaining said element in the same inactive condition for vehicles moving in either direction thereby unless there is another train ahead in the direction of traffic governed by said signal.
14. In a train control system for single track railroads equipped with a block signal system of the type described, the combination with two adjacent track circuits of said block signal system, a track element disposed opposite the adjacent ends of said track circuits and having a winding, and means governed automatically by each track circuit for independently establishing closed circuits of low resistance including said winding so long as that corresponding track circuit is not occupied.
15. In a train control system for single track railroads equipped with a block signal system of the type described, the combination with a signal, a magnetic core extending transversely of the track and disposed adjacent to the signal symmetrically with respect to the center line of the track, a winding on said core, and two separate circuits each including said winding and governed separately by track circuits on opposite sides of the signal.
16. In a train control system for single track railroads equipped with a block signal system of the type described, the combination with two oppositely located intermediate signals, a track element opposite said signals and disposed symmetrically with respect to the center line of the track, a circuit adapted when closed to maintain said

element in its inactive condition, means subjected to the same controlling influence as one of said signals for closing said circuit at times when the signal may indicate proceed, a second circuit also adapted when closed to maintain the track element in the same inactive condition, and means subjected to the same controlling influence as the other of said signals for closing the second circuit when that signal indicates proceed.

17. In a train control system for single track railroads, trackway equipment for co-operating inductively with car-carried apparatus through an intervening air gap comprising, two adjacent track circuits, a track element at the adjacent ends of said track circuits, said track element being normally inactive, and automatic means for maintaining said element inactive so long as either of said track circuits is not occupied.

18. A train control system for single track railroads for use in conjunction with a block signal system of the absolute-permissive-

25 block type described, comprising a track element located opposite a signal, said track element comprising a non-magnetized core, and automatic means for governing the controlling condition of each track element to correspond with the indication of the associated signal for trains moving in the direction of traffic governed by said signal, and for maintaining said track element inactive until the first car of a train traveling in the opposite direction has passed said element.

19. Inductive influence communicating means for block signal systems of single track railroads comprising, a track element having a core and a coil thereon and disposed symmetrically with respect to the center line of the track, and automatic means for including said coil in a closed deenergized circuit of low resistance for train movement thereby in either direction unless there is another train ahead.

20. An automatic train control system of the type described, the combination with a trackway block signal automatically governed in accordance with the presence or absence of other trains ahead, a track element

adjacent to said signal and having an inherent tendency to communicate the stopping influence, a non-energized control circuit for said element adapted when closed to render said element inactive, and automatic means for closing said circuit during the movement of a vehicle in either direction by said signal unless there is another train ahead of the signal in the direction of traffic governed thereby.

21. In a train control system, the combination with trackway signals and control means therefor constituting an absolute-permissive-block signal system of the general type described, track elements adapted to co-operate inductively through an intervening air gap with car-carried apparatus and arranged to communicate an influence to passing cars to conform with the indications of each signal, a polarized line circuit for governing each signal, and means controlled by said line circuit for governing the controlling condition of the corresponding track element.

22. In a train control system, the combination with trackway signals and control means therefor constituting an absolute-permissive-block signal system of the general type described, a track element at each signal comprising a core and a coil thereon, a circuit including said coil, and a polarized line relay governing each signal and also controlling said circuit.

23. In a train control system, the combination with trackway signals and control means therefor constituting an absolute-permissive-block signal system of the general type described, a track element for each signal comprising a non-magnetized core and a coil thereon, said track element being adapted to communicate an influence to a passing vehicle unless said coil is included in a circuit of low resistance, a polarized line relay governing each signal, and a circuit of low resistance for the coil of the corresponding track element governed by said relay.

In testimony whereof I affix my signature.

SEDGWICK N. WIGHT.
